UNITED STATES PATENT OFFICE.

EDGAR L. TENNEY, OF CHICAGO, ILLINOIS.

MATCH-SAFE.

No. 918,927.

Specification of Letters Patent. Patented April 20, 1909.

Application filed October 7, 1907. Serial No. 238,168.

To all whom it may concern:

Be it known that I, EDGAR L. TENNEY, a citizen of the United States, residing at Chicago, in the county of Cook and State of Illinois, have invented certain new and useful Improvements in Match-Safes, of which the following is a specification.

My invention relates to match-safes and the object of my invention is to provide a 10 magazine match-safe adapted to hold a box of matches, and wherein the box will constitute the magazine, the box being partially opened to allow the matches to feed therefrom as needed.

15 A further object is to provide a match-safe as mentioned of such construction that the matches will be fed therefrom to a position where they will be readily accessible.

20 A further object is to provide a match-safe as mentioned of such construction as to admit of the match box and matches being readily inserted or removed, and which will lock the lid of the box in open position to prevent the same from accidentally closing the 25 box when in the safe.

Other objects will appear hereinafter.

With these objects in view my invention consists generally in the match-safe illustrated in the accompanying drawings and in 30 various details of construction and arrangements of parts all as will be hereinafter fully described and particularly pointed out in the claims.

35 My invention will be more readily understood by reference to the accompanying drawings forming a part of this specification and in which,

40 Figure 1 is a perspective view of a match safe embodying my invention in its preferred form, Fig. 2 is a vertical section thereof, and Fig. 3 is a plan of the blank from which the match-safe is formed.

Generally speaking, my invention consists in a match-safe comprising a body portion of 45 suitable size to accommodate a match-box or one end thereof, a tray or trough from which the matches may be taken and a common bottom for the body portion and tray, of such construction as to wedge the box 50 against the front of the body portion of the safe to prevent the lid from being accidentally pushed downwardly, closing the box.

Referring to the drawings, A indicates generally the body portion and B the tray. 55 The body portion is rectangular in cross section and comprises the back, 1, the front

plate, 2 and the side members, 3. This portion of the device is of sufficient dimensions to receive one end of a match-box of the usual commercial size and may be high enough to 60 close the entire box, although, as shown in the drawing, it may be only high enough to retain the box in place. The lower portions of the members, 3 are enlarged to form the sides, 4 of the tray B, the bottom, 5 of which is 65 formed by extending the back member, 1 and curving it to conform to the semicircular sides, 4. In this manner the curved bottom, 5 is common to both the body portion and the tray. 70

The tray portion is extended forwardly of the wall or plate 2 a greater distance than the depth of the body portion, which brings the center of the curved sides forward of said plate. This makes the entire portion of the 75 bottom 5 which is below the body portion curve forwardly and downwardly, hence a match box placed in the body will have its lower end pushed forwardly and wedge the lid against the lower edge of the wall 2. 80

The device may be stamped out of a single piece of sheet metal folded into shape, the edges being joined in any suitable manner. By soldering or brazing the joints, a neat 85 strong match-safe may be formed. However, if desired, the edges may be fastened by providing the abutting edges with coacting tenons and slots 6 and 7 respectively.

In using the device, a box, 8, of matches having the usual sliding lid, 9, is placed end- 90 wise in the body portion of the safe as shown in Fig. 2, with the lid partially withdrawn. The bottom corner of the box engages the curved bottom, 5, and by sliding downwardly thereon shoves the lid of the box tightly 95 against the front plate, 2. This wedges the box in the safe and prevents the lid from being readily moved to close the box, all downward pressure thereon, tending to bind it still tighter in position. The curvature of 100 the bottom, 5 also causes the matches to be fed forward in the tray where they will be readily accessible; none of the matches getting under the end of the box where they cannot be readily reached. 105

Having described my invention what I claim as new and desire to secure by Letters Patent is:

1. A match safe formed of a single blank shaped to form a body portion consisting of a 110 back, the sides and a front plate, the back being extended to form a substantially semi-

circular bottom and an uncovered tray, said tray having semicircular sides formed by extending the lower portion of the sides of the body and the center of said semicircular sides and bottom being forward of said front plate and said body forming an unobstructed passage for a box of matches to said curved bottom, substantially as described.

2. A blank for a match safe comprising a 10 rectangular portion for the back and bottom of the device, a pair of semi-circular portions extending laterally in opposite directions from the lower corners of said rectangular portions for the sides of the tray, rectangular

extensions depending from the outer portion 15 of the lower edge of each of said semi-circular portions for the sides of the body portion and a rectangular portion extending inwardly from the inner edge of one of said depending portions for the front of the body portion 20 substantially as described.

In testimony whereof, I have signed my name to this specification in the presence of two subscribing witnesses.

EDGAR L. TENNEY.
